UNITED STATES PATENT OFFICE.

LOUIS T. WEISS, OF BROOKLYN, NEW YORK, ASSIGNOR TO RELIANCE BALL BEARING DOOR HANGER COMPANY, OF NEW YORK, N. Y., A CORPORATION OF NEW YORK.

DEVICE FOR OPERATING SLIDING DOORS.

1,217,249.

Specification of Letters Patent.

Patented Feb. 27, 1917.

Application filed October 5, 1916. Serial No. 123,904.

To all whom it may concern:

Be it known that I, LOUIS T. WEISS, a citizen of the United States, and residing in the borough of Brooklyn of the city of New York, county of Kings, in the State of New York, have invented certain new and useful Improvements in Devices for Operating Sliding Doors, of which the following is a specification, reference being had to the accompanying drawing, forming part hereof.

This invention relates to that class of devices for operating sliding doors, particularly for elevators, in which the door is moved to its closed position by the action of a spring through a toggle lever, one member of which is pivoted upon a relatively fixed point while the other is pivoted upon the door, and in which, in the opening movement of the door, the toggle is first broken and the opening movement of the door is continued by the application of force to the door by the hand of the operator. In some of such devices the operating handle has a limited free movement relative to the door, which limited free movement serves to break the toggle lock, and thereafter moves with the door to open the same against the force of the toggle spring, acting through an abutment carried by the door. In other devices, old in the art, the operating handle has no such free movement for the purpose of breaking the toggle, followed by a movement with the door in which it acts against an abutment on the door but has a continuous movement relative to the door throughout the movement of the door, sometimes having been formed as an extension of one member of the toggle. The invention is concerned with devices of the particular type last referred to and in accordance therewith the operating handle, pivoted on the door, acts continuously upon a cam surface carried by one member of the toggle and throughout the opening movement of the door acts continuously to flex the toggle more and more. The invention will be more fully explained hereinafter with reference to the accompanying drawing in which it is illustrated and in which,—

Figure 1 is a view in front elevation showing a portion of the sliding door and its support with the improved door operating devices.

Fig. 2 is a top view of the door operating

devices, the door and a portion of the wall being shown in section.

Fig. 3 is a detail view, on a larger scale than Fig. 1, showing the relation of the operating handle and the cam on the toggle member.

In the embodiment of the invention shown in the drawing, the wall *a* has secured thereto a track *b* on which is supported in any convenient manner, as by a carrier *c'*, a sliding door *e*. A door check *a'*, of any suitable construction, may be provided to cushion the closing movement of the door under the influence of the toggle spring. A toggle lever, comprising the two members *d* and *e*, has one member pivoted upon the door, as at *d'*, and the other member pivoted, as at *e'*, in a bracket *f* secured to the wall and preferably provided with a lip *f'* to limit the movement of the toggle in the closing movement of the door. A coiled spring *g* may be applied to the joint *h* of the toggle for the purpose of tending always to straighten the toggle and therefore to close the door. All of the parts thus far described may be formed and arranged to operate in any usual or suitable manner.

The toggle member *d* is provided at some convenient point with a cam surface *d²*, preferably on the upper side of an extension *d³* beyond the pivot *d'*, and the operating handle *k*, pivoted on the door, as at *k'*, is adapted to coöperate with such cam surface, as through a roller *k²* mounted on a pin *k³*. The weight of the handle *k* keeps the roller *k²* always in contact with the cam surface *d²*.

When the door is in its closed position the parts occupy the relative positions shown by full lines in Figs. 1 and 2, with the roller *k²* resting on the cam surface *d²*. When the door is to be opened the pressure of the operator's hand upon the operating handle *k* causes the roller *k²* to act upon the toe of the cam surface *d²* to break the toggle and continued pressure, also acting through the roller upon the cam surface, produces a further flexing of the toggle against the tension of the spring *g*, the relative movement of the operating handle with respect to the door and the pressure of its roller upon the cam surface continuing throughout the opening movement of the door which is accomplished by the flexing of the toggle.

I claim as my invention:

1. An operating device for sliding doors comprising a toggle having one member pivoted upon a fixed point and the other member pivoted upon the door, one of said members being formed with a cam surface, and an operating handle coöperating with the cam surface on the toggle first to break the toggle and then by continued pressure to flex the toggle further and open the door.
2. An operating device for sliding doors comprising a toggle having one member pivoted upon a fixed point and the other member pivoted upon the door, one of said members being formed with a cam surface and extended beyond the pivot on the door, and an operating handle coöperating with said cam surface first to break the toggle and then by continued pressure to flex the toggle further and open the door.
3. An operating device for sliding doors comprising a toggle having one member pivoted upon a fixed point and the other mem-

ber pivoted upon the door, one of said members being formed with a cam surface, an operating handle coöperating with the cam surface on the toggle first to break the toggle and then by continued pressure to flex the toggle further and open the door, and a spring applied to the toggle to straighten the same.

4. An operating device for sliding doors comprising a toggle having one member pivoted upon a fixed point and the other member pivoted upon the door, one of said members being formed with a cam surface, and extended beyond the pivot on the door, an operating handle coöperating with said cam surface first to break the toggle and then by continued pressure to flex the toggle further and open the door, and a spring applied to the toggle to straighten the same.

This specification signed this 29th day of September, A. D. 1916.

LOUIS T. WEISS.
